ROOF FLASHING

Filed Aug. 16, 1940

UNITED STATES PATENT OFFICE

2,250,548

ROOF FLASHING

William H. C. Ness, Los Angeles, Calif.

Application August 16, 1940, Serial No. 352,893

7 Claims. (Cl. 108—26)

This invention relates to a roof flashing.

Among the objects of the invention are to provide a roof flashing having an improved, built-in reglet which is so constructed that it does not weaken the parapet wall of the building; to provide a roof flashing construction which is bent or kinked in a superior manner along its foot portion to prevent cutting or chafing of the roofing materials; to provide a flashing construction which is built in such a manner as to permit the application of the plaster to the parapet wall before the roofing is laid; to provide a flashing construction that is more readily applicable to a variety of types of building construction; and further, to provide a flashing construction wherein the counter-flashing is gripped or sealed at a plurality of levels in such a manner that it is more securely held in its proper operative position. Other objects, advantages and features of invention will hereinafter appear.

Referring to the accompanying drawing, which illustrates what is at present deemed to be preferred embodiments of the invention—

Fig. 1 is a perspective and sectional view showing a fragment of the parapet and roof of a building with my improved flashing construction applied thereto.

Fig. 2 is a fragmental, vertical sectional detail showing a form supporting the flashing in position for being built into a parapet wall.

Fig. 3 is a vertical, sectional view of a modification.

Fig. 4 is a view similar to Fig. 3 but shows a second modification.

Referring in detail to the drawing, and describing first the form of the invention illustrated in Figs. 1 and 2, the concrete parapet wall 10 is shown supporting a reglet 11, said reglet consisting of a strip of sheet metal of considerable width which is doubled over upon itself throughout the greater portion of its width, its upper edge portion being directed backwardly, that is to say toward the outside of the building, thereby forming the double or two ply flange 12 which is embedded in the concrete wall 10.

The double flange 12 is not, however, the only embedded portion of the reglet, for from the front edge of the lower run of said flange the reglet has a back run or sheet portion 14 which overlies the face of the wall 10 to a considerable vertical extent, but at the lower edge terminates in an embedded foot flange 15 that is directed backwardly and downwardly.

The upper run of the aforesaid reglet top flange 12 is continued downwardly to form the

reglet apron 16, the counterflashing 20 having an enclosed upper portion 21 which is encased or housed between said apron 16 and the back sheet 14 and is thus gripped in such a manner as to be held in place.

Above its strip 21 the counterflashing has along its upper edge a forwardly inclined edge portion or flange 23, and along the lower edge of its said strip 21 the counterflashing has a backwardly and downwardly inclined relatively narrow strip 25. The three strips of the counterflashing which have been described impart to its upper portion a sinuosity corresponding in outline to the shape of the alined reglet strips between which it is gripped and the sheet material of which the reglet is made is of a sufficiently stiff character to provide for safely keeping in place the counterflashing after the latter has been pushed upwardly into place between the 20 apron and back sheet of the reglet.

Between its lower body portion and its sinuous upper part the counterflashing 20 has a relatively narrow strip or run 20x which, from the top of said body portion, extends upwardly at a 15 considerable backward inclination, said body portion having a definite backward inclination from above downwardly to its forwardly directed basal flange 55.

In Fig. 2 is shown a formwork 40 having the 30 two-ply reglet which has been described nailed to it by means of an upper horizontal row of nails 45 passing through it just below its doubled over upper edge, and a lower horizontal row of nails 46 passing through the run 14/ of said reglet just 35 above its basal flange 15.

Properly positioned holes for the nails will be punched through the reglet before it is nailed in place on the form as aforesaid. The lower portion of the reglet just above its basal flange 15 40 will be nailed down to the formwork as shown, but the nails 45 of the upper row will be only partly driven in, thus maintaining the flange 12 along the upper edge of the attached reglet directed backwardly from the formwork, as shown 45 in Fig. 2.

The construction of the parapet wall with the reglet built thereinto is accomplished by constructing the desired horizontal extent of formwork and attached reglet shown in Fig. 2 said 50 formwork being positioned with the face thereof to which the reglet is attached in alinement with the vertical plane which defines the inner face of a length of parapet wall about to be constructed, it being understood that suitable outer formwork will be provided so that the concrete may be filled

in between the two formwork members or sections. After the concrete has been filled in thereby embedding the upper and the lower reglet flange portions, then the body portion of the formwork is forcibly withdrawn and by the use of a chisel or other suitable cutting tool the portions of the nails which project from the set concrete will all be cut off flush with the inner face of the completed wall, so that the completed structure will present the appearance shown in Fig. 1.

It will be seen that the means which have been described for securing the reglet to the wall do not require that any hollow spaces remain in the completed wall, hence the building of the reglet into the wall does not weaken the latter. The double upper flange 12 of the reglet is upwardly inclined hence does not interfere with packing the concrete into the space subjacent to it. The portions of the nails 45 of the upper row which remain embedded in the completed wall aid in affording anchorage for the built-in reglet. Each of the lower nails 46 has a double headed portion 46a the section of the nail between and including its two heads affording secure anchorage in the completed wall for the lower part of the reglet.

After the roofing 50, with its upwardly directed marginal portion 51, has been laid, the lower or counterflashing is edged upwardly into its operative position as shown in Fig. 1. The reglet apron 16 may be sprung outwardly somewhat to facilitate moving of the counterflashing up into its fully inserted position such insertion of the counterflashing is facilitated by reason of adjacent runs or flat zones of both sheets of the outer part of the reglet joining each other at obtuse angles.

The double seal or locking members provided by the two opposed sinuous sheet portions of the reglet by its two most abrupt backward bent or interlocking parts or zones provides a positive means for holding the flashing in place. A definite and fixed amount of lap is also provided to insure protection against wind-driven rains.

Owing to the fact that the main straight run 20 of the counterflashing is deflected backwardly at 20x to a considerable extent in relation to the counterflashing strip 20 subjacent thereto, its lower edge portion which carries the flange 55 is caused to press firmly backward against the roofing 50 which extends upwardly therewith. This pressure will take place along the back side of the angle between the body portion of the counterflashing and its basal flange 55 and will keep rain from being blown up under the counterflashing, and will also prevent the counterflashing from being blown upwardly or becoming loose.

In Fig. 3 is shown a modification wherein the reglet is of a single ply character throughout its entire length. In this view a brick parapet wall 55a is shown upstanding above the level of the roof 56, and the reglet is shown as consisting of an upper horizontal portion 57 having a terminal upwardly directed flange 58, the reglet portion 57 resting on top of one of the brick courses 59 within which its flange 58 is embedded. The apron of this form of the reglet extends downwardly in a generally horizontal direction over the face of the parapet wall, like the reglet shown in Fig. 1 and, together with the counterflashing, being shaped the same, these parts are also lettered in the same manner.

In order to facilitate inserting the counterflashing 20 between the outer face of the brick

wall and the apron of the reglet due to the rough nature of the brick and mortar particles adhering thereto, I provide an angular sheet metal part 60. Said part has a horizontally extending flange 61 underlying and fastened in any suitable manner to the portion 57 and a vertically extending flange 62 overlying the front face of the brick wall and extending downwardly to a point adjacent the marginal portion 51 of the roofing.

In Fig. 4 is shown a second modification of the invention wherein also the reglet is of a single-ply character. In this view a vertical wooden parapet 75 is shown upstanding above the level of the roof 56 and the reglet is shown as consisting of a metal sheet having an approximately horizontal mid width portion 78 joined at approximately a right angle a vertical upper run 79. The wall 75 abuts against a framework 81 to which the upper reglet run 79 is secured by nails 82. The plaster wall 83 is then built upon the central reglet run 78 thus gripping it between itself and the top of the lower, wooden wall 75.

The depending or apron portion of this reglet and the counterflashing which cooperates with it are like the corresponding parts that have already been described and are therefore lettered in the same manner.

It should be understood that the present disclosures are for the purpose of illustration only and that this invention includes all modifications and equivalents which fall within the scope of the subject matter claimed.

What is claimed is:

1. A reglet having a flanged back portion for embedding in a wall, said reglet being provided with an apron depending from the embeddable portion thereof, said apron being provided with vertically spaced backwardly deflected portions joining each other at obtuse angles, and a counterflashing having deflected portions to match, underlie and interlock with said deflected portions of said reglet, said counterflashing being upwardly insertable behind said apron into its interlocked relation thereto.

2. The subject matter of claim 1 and, said counterflashing having a forwardly deflected portion and subjacent thereto a backwardly deflected portion to grip the marginal portions of applied sheet roofing, said two portions of said counterflashing extending in a generally downward direction and joining each other at an obtuse angle.

3. The subject matter of claim 1 and, said counterflashing having a forwardly deflected portion and subjacent thereto a backwardly deflected portion having a downwardly and forwardly directed foot flange, said two portions of said flashing superjacent to said foot flange joining each other at an obtuse angle.

4. In a flashing construction for the marginal portion of applied sheet roofing, a reglet having a back portion, an anchor flange whereby said reglet is securable to a parapet wall, said reglet having in its secured position a downwardly extending apron which in its general direction parallels said wall, said apron having a plurality of vertically spaced, rearwardly directed deflected portions, the lowermost of said deflected portions being positioned to rest normally in a detached manner against the face of the parapet wall to which it is attached, and a vertically extending counterflashing having in its upper portion forwardly deflected portions rearwardly interlockable with said deflected portions of said reglet, said counterflashing being insertable upwardly

behind said apron into operative position after the reglet has been installed upon a wall.

5. As an article of manufacture, a reglet consisting of upper and lower portions embeddable in a parapet wall and an intermediate depending, portion consisting of an apron and an underlying back sheet each of which has vertically spaced apart, narrow, forwardly directed bends or runs and a wider intervening substantially straight run which is backwardly directed at a less inclination than said runs which are above and below it, said bends and runs of said apron and back sheet fitting approximately into each other, to permit for the insertion of a counterflashing, and a counterflashing having a plurality of runs similarly contoured to be gripped between said intervening runs of the back sheet and apron of said reglet.

6. A flashing for a roof wall consisting of two sheet metal runs opposing each other in a face to face manner, the upper portions of said runs being directed backwardly for embedding in the wall, the remaining portion of each of said runs

extending in a generally downward direction for overlying a face portion of the wall, each of said downwardly extending runs having flat zones which join each other at obtuse angles, the angle 5 portions of the front run being loosely nested into corresponding angle portions of the back run, the lower edges of said runs being in a disconnected relation to each other, and a counter-flashing bent in correspondence with the bends 10 of said front and rear flashing runs, said counter-flashing being interlocked between said front and rear runs.

7. The subject matter of claim 6 and, said counterflashing having along its lower part a zone or run which is obtusely deflected backward to add to its efficiency in gripping marginal portions of sheet roofing material between itself and the wall, there being a forwardly directed flange along the lower edge of said counterflashing grip- 15 pable by a tool whereby to install and remove the counterflashing.
